UNITED STATES PATENT OFFICE.

JOHN J. LEE, OF DARWIN, OHIO.

LIFTER.

SPECIFICATION forming part of Letters Patent No. 600,432, dated March 8, 1898.

Application filed June 2, 1897. Serial No. 639,152. (No model.)

To all whom it may concern:

Be it known that I, JOHN J. LEE, a citizen of the United States, residing at Darwin, in the county of Meigs and State of Ohio, have invented certain new and useful Improvements 5 in Lifters; and I do hereby declare the following to be a full, clear, and exact description of the invention, such as will enable others skilled in the art to which it appertains to 10 make and use the same.

In most stores high shelving leads to the use of some kind of step-ladder, and this implies inconvenience and loss of time.

The object of this invention is to provide 15 an implement that shall conveniently serve for taking down and replacing upon the shelves boxes or packages that could not ordinarily be reached from the floor.

In the drawings, Figure 1 shows the device 20 in perspective, part of the handle or staff being broken out to shorten the figure. Fig. 2 shows that side of the implement opposite the principal one seen in Fig. 1. Fig. 3 is a section at 3 3, Fig. 2.

25 The body of the implement consists of a light staff A, having a broad flat head A', all preferably of wood. The upper end of this head meets centrally and perpendicularly a thin U-shaped flat bar or plate B and is rig- 30 idly fixed to the same. Upon one face of the staff and head slides in suitable guides C a rod D, having its upper end formed into a loop D', extending above and bending at right angles away from the head, so that the end 35 portion D² lies in a plane parallel to that of the bar or plate B. Below the loop, partly within a recess in the face of the body of the implement, the rod is inclosed in a long open coil D⁴ of light spring-wire, the coil normally 40 pressing upward upon the loop and reacting upon a support E. The rod terminates a short distance above the lower end of the staff in a hook D³, adapted to be engaged and drawn down with one finger of the hand that 45 may grasp the staff just below the hook. Now the thin ends of the bar B being pushed beneath any box or package the rod is drawn down until the box is clamped between the bar B below and the loop part D² above, and 50 is then removed from the shelf and lowered while so held. Upon the release of the hook the spring at once pushes the loop upward to

its normal position. It is to be observed that, if necessary, the staff may be grasped above the hook by the other hand, and that in so 55 doing the rod may be pressed against it firmly enough to still hold the box even when the hook is released.

It is often desired to handle tall narrow packages not well adapted to be held in the 60 clamps just described, and hence upon the opposite face of the staff and head there are provided laterally-moving jaws F for grasping such objects as bottles, jacketed or otherwise. These jaws are two bars centrally piv- 65 oted to the head at F' and having their free ends bent from the head at right angles at some distance above the plate B. To the lower ends of the bars, respectively, are piv- 70 oted links G, which are themselves pivoted 75 together at H and provided with an eye H', in which slides a headed rod I. The rod I is connected to an arm J, extending from the rod D through the staff in a long slot K. Now if the rod D is drawn downward the rod I 75 moves with it. When the head of the rod moves with it. When the head of the rod meets the eye H', further movement forcibly closes the jaws. Obviously, then, if the thin-edged loop of the bar B be pushed beneath a bottle or the like and if the rod D be drawn 80 downward the bottle will be grasped laterally and at the same time supported below—that is, it will be so held that it may be readily and safely removed from the shelf and lowered. The jaws may advantageously con- 85 verge slightly to hold the bottle with more absolute security.

It is evident that articles may be placed in either clamp and returned to the shelves. If when the bar or plate B is withdrawn from 90 beneath the article the latter is left a little in front of the proper position, it may be pushed back with the side of the head B'.

What I claim is—

1. The combination with the staff having 95 the integral flat head projecting laterally beyond all other parts of the device, of the central fixed bar or plate projecting perpendicularly from one broad face of the head, the rod sliding longitudinally in guides upon the 100 staff and having at its lower end the hook and at its upper end the loop with branches held parallel to the staff in guides and with its upper portion bent above the bar or plate

into a plane parallel to the same, and the spring resisting downward sliding of the rod.

2. The combination with a staff and a thin bar or plate projecting from its upper end at 5 right angles, of crossed bars centrally pivoted to the staff, projecting above said upper end and bent outward to form jaws parallel to said bar or plate, a rod sliding in suitable guides on said staff, and connections where-
10 by downward sliding of said rod swings said bars upon their pivot and causes the mutual approach of said jaws.

3. The combination with the staff slotted through at the proper point, of the bar or 15 plate fixed to the upper end of the staff and projecting upon both sides thereof, the rod

sliding in suitable guides upon the staff, having its upper end bent outward parallel to said bar or plate, and also having an arm ex-
10 tends through said slot, laterally-closing 20 jaws upon the opposite sides of the staff and parallel to said bar or plate, a spring arranged to resist downward sliding of said rod, and devices connected with said rod and arranged to close said jaws when the rod slides down-
25 ward.

In testimony whereof I affix my signature in presence of two witnesses.

JOHN J. LEE.
